[57] **CLAIM**

The ornamental design for a set of brackets for mounting in the interior of a vehicle for supporting skis, as shown and described.

DESCRIPTION

FIG. 1 is a perspective view of a set of brackets for mounting in the interior of a vehicle for supporting skis showing my new design, it being understood that the broken lines are for illustration purposes only; FIG. 2 is an enlarged rear elevational view of one of the brackets of the set shown in FIG. 1; FIG. 3 is a right side elevational view of FIG. 2; FIG. 4 is a left side elevational view of FIG. 2; FIG. 5 is a top plan view of FIG. 2; FIG. 6 is a bottom plan view of FIG. 2; FIG. 7 is an enlarged front elevational view of the second bracket of the set shown in FIG. 1; FIG. 8 is a left side elevational view of FIG. 7; FIG. 9 is a right side elevational view of FIG. 7; FIG. 10 is a top plan view of FIG. 7; FIG. 11 is a bottom plan view of FIG. 7.
